ROTARY PUMP

William Ward Davidson, Evanston, Ill.

Application October 16, 1936, Serial No. 105,958

14 Claims. (Cl. 103—121)

This invention relates to improvements in rotary pumps, and has special relation to rotary pumps particularly adapted for pumping liquids, such as water, gasoline, oil, etc.

The object of the invention is to provide a rotary pump for this purpose, which shall have high efficiency in the use of power; in which the internal friction shall be reduced to a minimum; in the operation of which the leakage shall be inconsiderable; and in which the pressure shall be practically balanced on all moving parts thus reducing friction and the power consumption.

An important feature of the invention relates to simple means for sealing the bearings against the liquid operated upon, and particularly on the pressure side of the pump.

A further feature relates to a pump, for the purpose specified, in which the operating parts of the pump are immersed in the liquid being pumped.

A further feature relates to simple means of relieving certain parts of all pressure, that is, of maintaining such parts under atmospheric pressure.

Further features and advantages will become apparent and the invention will be more readily understood from the following description taken in conjunction with the accompanying drawings, forming part of this specification, and in view of the appended claims.

In said drawings:

Fig. 1 is a longitudinal, vertical, central section of a pump which embodies the invention in what I now consider as a preferable form;

Figs. 2, 3 and 4 are transverse, vertical sections on the lines 2—2, 3—3 and 4—4 respectively of Fig. 1;

Fig. 5 is a fragmentary, vertical, longitudinal section on the line 5—5 of Fig. 2;

Fig. 6 is a fragmentary, vertical, transverse section on the line 6—6 of Fig. 1;

Fig. 7 is a fragmentary, side elevation of one of the cylinder heads particularly showing the inlet to the cylinder;

Fig. 8 is a fragmentary, central, longitudinal section of the cylinder assembly and taken on the line 8—8 of Fig. 9;

Fig. 9 is a transverse section on the line 9—9 of Fig. 8;

Fig. 10 is a fragmentary transverse section on the line 10—10 of Fig. 8;

Fig. 11 is a fragmentary, side elevation of the pump rotor and its supporting shaft or shank;

Fig. 12 is a fragmentary, side elevation of the inner end portion of the rotor shaft;

Fig. 13 is a perspective view of the pump vane;

Fig. 14 is a perspective view of the rocking or oscillating member in which the pump vane is mounted;

5 Fig. 15 is a view similar to Fig. 1, but showing an embodiment in which some parts are modified;

Fig. 16 is a view similar to Fig. 1 showing other slight modifications;

Fig. 17 is a view similar to Fig. 1, and showing 10 a different means for driving the pump;

Figs. 18 and 19 are transverse, vertical sections on the lines 18—18 and 19—19 respectively of Fig. 17;

15 Fig. 20 is a side elevation of the rotor and its shaft as shown in Fig. 17;

Fig. 21 is a longitudinal, central section of the cylinder as shown in Fig. 17, one cylinder head being removed;

Fig. 22 is an end elevation of the rotor and vane 20 assembly as shown in Fig. 17;

Fig. 23 is a side view and Fig. 24 is an end view, of the pump vane shown in Fig. 17;

Fig. 25 is an end view of the rocking member in which the vane is mounted as shown in Fig. 17;

25 Fig. 26 is a vertical, longitudinal section on the line 26—26 of Fig. 25; and

Fig. 27 is a fragmentary, longitudinal, central, section of the rotor and cylinder and taken on the line 27—27 of Fig. 18.

30 Important features which adhere throughout the several different embodiments of the invention are the submergence of the cylinder and rotor in the liquid being pumped and the balanced discharge of the liquid from the rotating parts 35 of the pump.

In the preferred form as portrayed in Figs. 1 to 14 inclusive, the pump comprises a frame 30 in which there is a centrally arranged chamber 31 which is extended up to form a dome 32 provided with an inlet 33 for the liquid to be pumped.

This chamber is closed except for the liquid inlet 33 and in the lower part thereof the operating parts of the pump designated generally by A are arranged.

45 The frame 30 has a horizontal base 34. An extension 35 is provided extending out horizontally from one side of the chamber 31 concentric with the pump A, and a second somewhat similar extension 36 extends out horizontally and opposite to the extension 35, the extension 36 being integral with a flanged head 37 which closes one side of the central chamber 31.

These extensions 35 and 36 are arranged to rotatably carry the pump A.

55 As shown, the frame 30 has an opening 38 at

one side which is closed by the head 37 and through which the pump A can be entered into the chamber 31. The head 37 is secured to the frame 30 by bolts 39.

The pump A comprises a rotatable cylinder 40 which, as shown, is built up of a cylindrical ring 41 which forms the cylindrical wall of the cylinder and closed at one end by a head 42 secured by bolts 43 (Fig. 2) and provided with an integral central bearing stem or shank 44 arranged to extend centrally through the frame extension 36 and be rotatably supported therein. The cylinder is closed at its opposite end by a head 45 similarly secured to the cylindrical ring 41. The pump is provided with a bearing spindle or shank 46 which extends opposite to the shank 44 and is adapted to be rotatably supported in the frame extension 35.

The head 45 of the cylinder A is provided with a central opening 47 (Fig. 8) through which the inner end 48 of the bearing shank 46 extends into the cylinder of the pump and a rotor 49 is carried on said inner end 48 of the shank 46 and is secured thereto, as by key 50, to rotate therewith. The rotor 49 operatively fits between the inner faces of the cylinder heads 42 and 45. It is smaller in diameter than the internal diameter of the cylindrical ring 41, and is arranged in eccentric tangential relation to the cylinder thereby providing a crescent shaped pumping space or chamber 51 (Fig. 9). The arrangement is such that as the pump A is rotated the liquid to be pumped is drawn into said space 51 and then forcibly discharged therefrom.

For rotating the pump A the shank 44 may be extended beyond the frame extension 36 as indicated at 52 in Fig. 1 and power applied thereto by any suitable means, not shown.

The pump is provided with a radial vane 53 (Figs. 9 and 10) to divide the inlet side of the chamber 51 from its discharge side. The vane 53 is fixed in the cylindrical wall of the pump, being secured in a slot 54 by a key pin 54' and projects inwardly into the rotor 49, and it is flexibly connected to the rotor by a cylindrical rocking member 55 mounted in a longitudinal, cylindrical opening 56 in the periphery of the rotor. The member 55 is provided with a central, longitudinal slot 57 in which the vane slidingly fits.

To permit the liquid to enter the pump from the chamber 31, that is to enter the pumping space 51, the cylinder heads 42 and 45 are respectively provided with ports 58 and 59 at the suction side of the vane 53. To provide an outlet for the liquid from the pump, that is from the pumping space 51, a radial passage 60 is provided in the rotor 49, and is extended into the inner extension 48 of the bearing shank 46 as shown at 61 and the bearing shank 46 is provided with a central passage 62 connecting at its inner end with the discharge passage 61 and opening at its outer end into a discharge chamber 63 which is provided with a discharge opening 64 through which the liquid is discharged from the pump.

The eccentric relation of the cylinder 40 and the rotor 49 is shown by the two center lines 65 and 66 on Figs. 2 and 3, the lower centerline 65 being the centerline of the cylinder 40 and the right hand bearing 36, and the upper centerline being that of the rotor 49 and the left hand bearing 35.

The means for driving the pump has been explained, the power being applied directly to the cylinder 40, and the rotor 49 is driven through

the vane 53 which, as has been explained, is rigidly mounted in the wall of the cylinder and has a flexible driving connection with the rotor 49 through cylindrical plug member 55.

It will be observed that the vane 53 has an extended portion 67 which fits within a cut-a-way portion 68 at the corresponding end of the rocker 55. The purpose of this arrangement is to give the vane additional bearing area inasmuch as it is used to drive the rotor and in the particular pump which is shown in the drawings, the eccentricity between the rotor and the cylinder is such that when the vane is 180° away from the point of tangency between the rotor and the cylinder, the inner margin of the principal portion of the vane is withdrawn approximately to the center of the rocker with the result that there is a tendency to concentrate driving stresses along the outer margins of the rocker instead of more or less evenly distributing them over the bearing surfaces of the rocker. The extension 67 minimizes this tendency and the rotor 49 is slotted at 69 to accommodate the extension of the vane.

In the form of pump being described the cylinder shank 44 is rotatably carried in ball bearings 70 arranged within the outer end of the frame extension 36 and 71 arranged within the inner end of same.

The bearing shank 46 of the rotor is likewise rotatably supported within the frame extension 35 by ball bearings 72 arranged within the outer end of the extension 35 and 73 arranged within the inner end of said extension. Each of the ball bearings, as usual, consists of an outer ball race secured to the outer stationary member, an inner ball race secured to the rotating member and a ring of balls between the two race members.

The outer race member 74 of the bearing 70 is secured in the outer end of the frame extension 36 in a counter-bore 75 which provides a shoulder 76 and the race 74 is clamped against the shoulder 76 by a closure flange 77 which is secured to the outer end of the extension 36 by bolts 78.

The flange 77 has a central opening 79 through which the shank 44 projects and the flange is provided with a plurality of internal grooves 80 which assist in preventing the free escape of leakage along the shank.

The outer ball race 81 of the inner ball bearing 71 is likewise secured in a counter-bore 82 in the extension 36 which provides a shoulder 83 and the race is clamped against this shoulder by a relatively thin flat ring 84 which is held against a circumferential shoulder 85 adjacent to the inner end of the extension 36. The ring 84 is held against the shoulder 85 by the cylinder head 42, spacer rings 86 and 87 being drive fitted on the shank 44 and interposed between the outer face of the cylinder head and the inner face of the ring 84. As will be explained these spacer rings have other important functions.

The inner ball races 88, of the outer ball bearing 70, and the inner ball race 89 of the inner ball bearing 71 are mounted directly on the shank 44 and are held in proper longitudinally spaced positions within their respective outer ball races by the cylinder head 42 at the inner end, a threaded clamping nut 90 on the shank 44 near its outer end and the spacer rings 86 and 87 and a suitable spacer sleeve 91 between the two inner ball races 88 and 89. The outer end portion 92 of the shank 44 is reduced in diameter to provide a circumferential shoulder 93 against which the nut 90 is firmly clamped. The flanged closure plate 77 is provided with a suit-

able space 94 to receive the nut 90 and let it rotate freely with the shank 44.

As the ball bearings would permit the free escape of the liquid from the chamber 31, I seal the chamber at the inner end of the extension by suitable means to be now described.

It is of course desirable to seal the chamber 31, around the shank 44 with means which will not appreciably add friction and to this end the sealing means comprises a yielding thin, sheet metal bellows ring 95 interposed between a circumferential shoulder 96 on the spacer ring 86 and the inner face of a ring flange 97 rigidly secured in a counter-bore 98 at the inner end of the extension 36. This flange ring 97 is secured rigidly to the frame extension 36 by screws 99. The inner end of the bellows device comprises a ring 100 which fits on the spacer 86 and bears against the shoulder 96, forming a running joint therewith, the inner end of the thin sheet metal bellows being sealed to the outer edge of the ring 100 as by being soldered thereto. The outer end of the sheet metal bellows is sealed to the inner edge of the flange ring 97 as by being soldered thereto. The inner edge of the fixed flange ring 97 is free of any rotating part.

Between the flange ring 97 and the ring 84 there is provided a free space 101 which forms a chamber to catch any liquid which might possibly pass the sealing device. In order to prevent any accumulation of liquid in the catch chamber 101 it is provided with a suitable drain opening 102 opening out through one side of the pump frame and to permit the leakage to drain out freely, the chamber 101 is connected to the atmosphere at its top by a free vent opening 103. The ring 87 associated with the seal bearing 71 is drive fitted on the shaft 44 and has a laterally extending flange 104 which cooperates with the inner surface of the ring 84 to form the desired seal.

An arrangement similar in principle consisting of spaced seals separated by an opening into which the liquid operated on by the pump or the lubricant in the bearing may leak in the event of partial or complete failure of either of the seals, is used on the other side of the pump between the cylinder head 45 and the bearing 73 and again at the end of the shaft 46 between the discharge chamber 63 and the bearing 72.

The arrangement is such that there is a free running contact between these two rings and the outer edge of the fixed ring 84 is so formed as to be free of the inner ball race 89 to avoid any friction at this point.

The chamber 31 is similarly sealed around the opposite shank 46 except that it is so arranged that there is a slight end play allowed to the rotor and its shank so that the rotor will not be bound between the two cylinder heads of the pump cylinder.

It will be seen that the ring 105 at the inner end of the bellows device which seals the chamber 31 around the shank 46, bears directly against the cylinder head 45 instead of against a spacer ring as at the other side of the cylinder, and that the outer spacer ring 106, which is drive fitted on the shaft, and which is similar to the outer ring 87 at the other side bears against a shoulder 107 on the shank 46 instead of against an inner spacer ring as at the opposite sides, in other words the rotor and its shank are not definitely held longitudinally of the shank, independently of the cylinder.

If the discharge of the liquid were axially

through the outer end of the shank 46 there would be a back pressure which would tend to force the rotor to the right, Fig. 1, and thus cause friction between the rotor and the cylinder head 42. To counteract this the liquid is discharged radially by a construction now to be described.

The outer end of the shank 46 is externally screw threaded as shown at 108 to receive a discharge cap 109 which has an internally screw-threaded nozzle 110 to fit on the outer end of the shank 46. The cap 109 is closed at its outer end by a wall 111 and its periphery is provided with a series of oppositely disposed radial discharge openings 112 through which the liquid escapes into the chamber 63.

For the purpose of sealing the chamber 63 against the escape or leakage of the liquid around the shank 46 there is provided a bellows packing device 113 similar to those already described and so arranged that the shank and rotor are yieldingly held axially of the rotor to prevent the development of unnecessary friction between the rotor and the cylinder. The construction of the bellows packing next to the cylinder head 45 and at the outer end of the shank 46 provide catch chambers 114 and 115 respectively which as described in relation to the catch chamber 101 are provided with open drains and vent openings.

The construction of the bellows packings at each end of the pump cylinder provide a free space 116 between the cylinder head 42 and the adjacent wall of the chamber 31 and a similar space 117 at the opposite end of the cylinder and which spaces permit the free flow of the liquid from the chamber 31 through the cylinder ports 58 and 59 into the cylinder.

Referring now particularly to Figs. 1, 2, 5, 6, 7, 8 and 9, the cylinder rotates in the direction of the arrows 118 Fig. 2 and 119 Fig. 6 and from Fig. 9 it will be readily understood that just as the rotor is passing the point shown in Fig. 9, the fluid in the pump chamber 51 could escape back through the inlet openings. To prevent this action, stationary stop plates 120 at one side and 121 at the other side are provided which cover the inlet ports 58 and 59 respectively during such period of rotation of the cylinder.

These stop plates as best shown in Fig. 5 are secured to the stationary ring plates 97 of the sealing devices at the ends of the cylinder and have flat faces which contact with the outer faces of the cylinder heads.

It will be noted that the forward sides of the cylinder ports are extended forward to some extent as shown at 122 toward the outer faces of the cylinder heads, and the walls of the ports which are first uncovered are inclined inwardly toward the cylinder and this permits the liquid to easily flow into the cylinder and assure the filling of the pump space 51.

Referring now to Fig. 15, it will be seen that the construction illustrated is the same as that already described in so far as the pump, its method of driving, and the means of sealing the chamber 31 is concerned, but that a different means is provided for sealing the delivery chamber 63.

The means for this purpose, as shown in Fig. 15, comprises a delivery nozzle 123 provided with an externally screw threaded connection projection 124 adapted to be received within the outer end of the central delivery passage 62 in the rotor shank 46. The nozzle 123 provides a circumfer-

ential shoulder 125 at the outer end of the shank 46 and a spacer sleeve 126 is interposed on the shank 46 between said shoulder 125 and the inner ball race 127 of the outer ball bearing 72 on the shank 46. The outer end portion 128 of the frame extension 35 is cut off from the main inner portion of said extension by an open notch or gap 129. The part 128 contains the discharge chamber 63 and its inner wall is provided with a cylindrical opening 130 in which the spacer sleeve 126 fits tightly. To prevent possible leakage along the outer surface of this sleeve there is provided, at its inner end, a stuffing box 131 containing compressible packing 132 and a stuffer gland 133 is provided. The gland fits on the outer surface of the spacer sleeve 126 and is adapted to be forced into the stuffing box by any suitable means such as screw bolts 134 to hold the packing 132 properly compressed.

As in the first form described, the delivery nozzle 123 has a plurality of radial and oppositely disposed delivery openings 135 which balance each other.

In Fig. 16 there is shown a construction with plain sleeve bearings instead of the ball bearings shown in the forms already described. In this present form a packing for the outer end of the shank 46 of the rotor is provided which is the same as that shown in Fig. 15.

The shank 44 of the cylinder is rotatably mounted in elongated bearing sleeves 136, at its outer end, and 137 at its inner end separated by a chamber 138 within the frame extension and the chamber 138 is adapted to be filled with a heavy lubricating grease, through a grease cup 139, which, together with the elongated bearing sleeves, effectively prevents the leakage of the liquid particularly as it is only necessary to pack or seal against the suction side of the pump.

Likewise the shank 46 of the rotor is mounted in a relatively long sleeve bearing 140 at its inner end which can likewise be supplied with heavy bearing grease through a grease cup 141.

As this pump is generally of simpler construction than the forms heretofore described it is provided with simpler sealing means for the inlet chamber 31.

The cylinder shank 44 is enlarged at its inner end as shown at 142 and a circumferential shoulder 143 is provided which contacts with the inner end 144 of the inner sleeve bearing 137.

On the opposite side the shank 46 of the rotor is similarly enlarged at its inner end, as shown at 142*, and a circumferential shoulder 143* is provided which contacts with the inner end 144* of the sleeve bearing 140. Thus the cylinder and rotor are held against longitudinal movement outwardly. This construction retains the cylinder and the rotor in position free of the walls of the chamber 31.

A simple known form of packing is used to seal the chamber around the enlargements of the shanks 44 and 46. Each of these packings comprise an L-shaped ring casing 145 which fits in a counter-bore 146 in the wall of the chamber 31 surrounding the shank. Within this casing 145 is arranged an L-shaped packing ring member 147 one leg of which fits on the enlarged part of the shank and the other leg of which is arranged in contact with the radial wall 148 of the L-shaped casing. The inner leg 149 of the L-shaped packing is tapered down toward the chamber 31 to quite a thin edge and this packing

ring is made of some yielding material such as leather or a suitable composition.

The slight pressure within the chamber 31 tends to cause the thin edge of the packing ring 149 to hug the shank and thus prevent leakage at this point. To assist in this action and prevent the possible lifting of this thin edge there is a pressure ring 150 provided, the inner part of which is flared so as to be inclined nearly parallel to the thin tapered edge of the packing and this ring is yieldingly pressed against the packing by a spring washer 151 which is held within the casing member 145 by a second L-shaped casing ring member 152 which fits within the member 145 and backs up the spring washer 151.

As the chamber 31 constitutes the suction chamber of the pump the pressure therein is quite slight and it has been found that this form of packing is effective and does not add appreciable friction.

Referring now to Figs. 17 to 26 inclusive;

In these figures there is illustrated a simple form of the invention and including a gear driven pump, especially adapted for use in sizes too large to be connected directly to an electric motor and for use in the pumping of oil or like liquids. In this form there is a hollow frame or casing 153 having a bottom wall 154 and side walls forming a chamber 155 which is closed at one end by a removable head 156 secured in place by bolts 157.

A pump B is rotatably mounted within the chamber 155 and comprises a rotatable pump cylinder 158 closed at its ends by opposed heads 159—160 which are secured to the cylinder by bolts 161.

Within the cylinder is a rotor 162 operatively fitting between the inner flat faces of the cylinder heads and arranged, as before, in eccentric tangential relation to the cylinder to provide a crescent shaped pumping space or chamber 163.

For rotatably supporting the cylinder and rotor in their eccentric tangential relation there are provided oppositely disposed fixed bearing members 164—165 each comprising a base flange 166, at one end adapted to be secured to a vertical end wall 167 of the pump frame, and at the other end to be secured to the inner face of the frame head 156. Each bearing member is provided with a cylindrical bearing projection 168 and the pump cylinder 158 is rotatably mounted on the outer cylindrical surfaces of these projections, the cylinder heads being provided with a hollow cylindrical bearing projection 169 adapted to operatively fit on the outer surfaces of said fixed bearing projections 168 and be rotatably supported thereon.

The rotor 162 has a centrally disposed bearing shank 170 at each end which shanks are received within longitudinal bearing openings 171 in the rigid opposed bearings.

The bearing openings 171 are arranged in eccentric relations to the outer bearing surfaces of the bearing projections similar to the eccentric relation of the cylinder 158 and rotor 162 and maintain these parts in their operative relation.

As in the forms heretofore described a vane 172 is fixed in radial position in the cylinder wall and has a similar flexible connection with the rotor, that is, a cylindrical plug 173 is arranged in the periphery of the rotor and is longitudinally slotted, as shown at 174 to receive the vane 173. In this form the vane has an inwardly extending projection 175 at each end and the slot 174 in the plug 172 is cut clear through the plug at its

ends to receive these projections. These projections add to the radial engagement of the plug and vane and assist in preventing any cramping or binding between these two parts.

The heads 159 and 160 of the cylinder are provided with inlet ports 176 at the suction side of the vane 172 to admit the liquid from the pump casing to the pump and, as before, a discharge passage 177 is provided extending radially through the rotor at the pressure side of the vane 172 and communicating at its inner end with a central discharge passage 178 extending longitudinally through the rotor shanks 170. This discharge passage 178 extends from end to end of the rotor and its shanks and communicates at its ends with a passage 179 formed in the wall of the pump casing and provided at one end with a delivery opening 180.

For applying power to the cylinder 158 to rotate same and operate the pump the cylinder is provided with a ring of gear teeth 181 on its outer cylindrical surface and a toothed pinion 182 is provided to mesh therewith. The pinion is secured upon the inner end of a drive shaft 183 which extends through a frame extension 184 and is provided, on its outer end, with suitable means for driving same such as a belt pulley 185 secured thereto.

The pinion is arranged within the pump casing and as the material intended to be pumped is of a lubricating nature, no special arrangement is provided for lubricating the various bearings and the gears.

As the shaft 183 extends outside of the casing, simple packing means 186, are provided to prevent the escape of the liquid at the outer end of the shaft. Preferably this packing means 186 is similar to the packings described in relation to Fig. 16 and does not require special description.

An inlet 187, for the liquid to be pumped, is shown as arranged in the upper part of the pump casing.

As many other modifications of the invention will readily suggest themselves to one skilled in the art, I do not limit or confine the invention to the specific details of construction or operation herein shown and described.

Throughout the appended claims, the term "rotor" is used in a broad sense and is intended to include all forms of inner pump members which by some form of rotary motion cooperate with the cylindrical pump chamber to produce a pumping action.

I claim:

1. In a rotary pump of the kind described, a pump frame having a supply chamber, a rotary pump cylinder arranged in the chamber and adapted to be submerged in the supply liquid, heads for the cylinder, inlet ports extending longitudinally through the heads, a rotor within the cylinder and arranged in eccentric tangential relation thereto, a pumping vane having engagement with the cylinder and rotor, said inlet ports arranged on the suction side of said vane, and means in said chamber for closing said ports during the period of the cycle when the vane is at and closely adjacent to the point of tangency between the rotor and the cylinder, said port closing means comprising fixed segmental plates arranged in contact with the outer faces of the cylinder heads.

2. In a rotary pump of the kind described, a pump frame having a supply chamber, a rotary pump cylinder arranged in the chamber, and

adapted to be submerged in the supply liquid, heads for the cylinder, inlet ports extending longitudinally through the heads, a rotor within the cylinder and arranged in eccentric tangential relation thereto, a pumping vane having engagement with the cylinder and rotor, said inlet ports arranged on the suction side of said vane, and means in said chamber for closing said ports during the period of the cycle when the vane is at and closely adjacent to the point of tangency between the rotor and the cylinder, said cylinder and said rotor having bearing shanks, and said frame being provided with bearings in which said shanks are rotatably mounted, yielding means sealing the chamber around said shanks, auxiliary sealing means around said shanks beyond the yielding sealing means, the arrangement being such that drip catch chambers are provided between the two sealing means around each said shank, said drip chambers being open to the atmosphere, and means for draining said drip chambers.

3. In a pump for handling liquids, a casing provided with a fluid inlet chamber, a rotary pump in the chamber comprising a rotatable cylinder having an axially extending trunnion shaft, a rotor mounted in the cylinder in eccentric tangential relation and having an oppositely axially extending trunnion shaft, means for introducing fluid from the chamber into the cylinder and discharging it through one of the shafts, means for rotating the cylinder and rotor to produce a pumping action therebetween, bearing supports for both shafts positioned on the outside of the inlet chamber, and sealing means on both shafts between the bearing supports and the inlet chamber.

4. In a pump for handling liquids, a casing provided with a fluid inlet chamber, a rotary pump in the chamber comprising a rotatable cylinder having an axially extending trunnion shaft, a rotor mounted in the cylinder in eccentric tangential relation and having an oppositely axially extending trunnion shaft, means for introducing fluid from the chamber into the cylinder and discharging it through one of the shafts, means for rotating the cylinder and rotor to produce a pumping action therebetween, bearing supports for both shafts positioned on the outside of the inlet chamber, and sealing means on both shafts between the bearing supports and the inlet chamber, said sealing means comprising spaced seals separated by an opening into which liquid or lubricant, as the case may be, may leak upon the partial or complete failure of either of the seals.

5. In a pump for handling fluids, a casing provided with a fluid inlet chamber, a rotary pump in the chamber comprising a rotatable cylinder having an axially extending trunnion shaft, a rotor mounted in the cylinder in eccentric tangential relation and having an oppositely axially extending trunnion shaft, means for introducing fluid from the chamber into the cylinder and subsequently discharging it through one of the shafts, means for rotating the cylinder and rotor to produce a pumping action therebetween, bearing supports for both shafts positioned on the outside of the inlet chamber, means for introducing a lubricant into the bearing supports, a discharge chamber associated with one of said shafts, and sealing means located between the discharge chamber and the adjacent bearing and between the fluid chamber and the bearing associated with the other shaft, said sealing means each

comprising spaced seals separated by an opening into which fluid or lubricant, as the case may be, may leak in the event of partial or complete failure of either of the seals.

6. In a rotary pump for handling liquid possessing poor lubricating properties, a rotatable cylinder having an axially extending trunnion shaft, a rotor eccentrically mounted within the cylinder having an oppositely axially extending trunnion shaft, bearings for said shafts located wholly outside of the pump cylinder, means for introducing lubricant into said bearings, a discharge chamber at the end of one of the shafts for receiving high pressure liquid, means for sealing the discharge chamber from the adjacent bearing including spaced seals separated by an opening into which the liquid or lubricant, as the case may be, may leak in the event of partial or complete failure of either of the seals, an intake chamber associated with the other shaft, and means for sealing said intake chamber from the adjacent bearing, said last-named means including spaced seals separated by an opening into which liquid or lubricant, as the case may be, may leak in the event of partial or complete failure of either of the last-named seals.

7. In a rotary pump for handling fluids, a fluid inlet chamber, a hollow rotatable cylinder mounted in the chamber for rotation about its axis, a rotor within the cylinder mounted in eccentric tangential relation with the cylinder for rotation about its axis, a single vane connecting the rotor and the cylinder and dividing the pump chamber therebetween into intake and discharge stages, an inlet passage through the cylinder adjacent to the periphery of the cylinder and located on one side of the vane, a discharge passage extending through the rotor and located on the other side of the vane, a valve for the intake passage, and means whereby the fluid inlet chamber is kept in open communication with the pump chamber except for the brief interval during which the vane is at and immediately adjacent to the point of tangency between the cylinder and the rotor at which time the intake passage is closed by said valve.

8. In a rotary pump for handling fluids, a hollow rotatable cylinder mounted for rotation about its axis, a rotor within the cylinder mounted in eccentric tangential relation with the cylinder for rotation about its axis, a single vane connecting the rotor and cylinder and dividing the pump chamber therebetween into intake and discharge stages, inlet and discharge passages communicating with the pump chamber on opposite sides of the vane, a valve for the intake passage, and means whereby the fluid intake passage is kept in open communication with the pump chamber except for the brief interval during which the vane is at and immediately adjacent to the point of tangency between the cylinder and the rotor at which time the intake passage is closed by said valve.

9. In a rotary pump for handling fluids, a fluid inlet chamber, a hollow rotatable cylinder mounted in the chamber for rotation about its axis, a rotor within the cylinder mounted in eccentric tangential relation with the cylinder for rotation about its axis, a single vane connecting the rotor and the cylinder and dividing the pump chamber therebetween into intake and discharge stages, an inlet passage through the cylinder adjacent to the periphery of the cylinder and located on one side of the vane, a discharge passage extending through the rotor and located on

the other side of the vane, a valve for the intake passage, and means whereby the fluid inlet chamber is kept in open communication with the pump chamber except for the brief interval during which the vane is at and immediately adjacent to the point of tangency between the cylinder and the rotor at which time the intake passage is closed by said valve, said means comprising a fixed block having sliding engagement with the cylinder and being located so that the inlet passage through the cylinder is covered by the block for a portion of each cycle of revolution.

10. In a pump for handling liquids, a casing provided with a fluid chamber, a rotary pump in the chamber comprising a rotatable cylinder having an axially extending trunnion shaft, a rotor mounted in the cylinder in eccentric tangential relation and having an oppositely axially extending trunnion shaft, means for introducing fluid into the cylinder and discharging it including a passage through one of the shafts, means for rotating the cylinder and rotor to produce a pumping action therebetween, bearing supports for both shafts positioned on the outside of the chamber, and sealing means on both shafts between the bearing supports and the chamber.

11. In a pump for handling liquids, a casing provided with a fluid chamber, a rotary pump in the chamber comprising a rotatable cylinder having an axially extending trunnion shaft, a rotor mounted in the cylinder in eccentric tangential relation and having an oppositely axially extending trunnion shaft, means for introducing fluid into the cylinder and discharging it including a passage through one of the shafts, means for rotating the cylinder and rotor to produce a pumping action therebetween, bearing supports for both shafts positioned on the outside of the chamber, means for introducing a lubricant into the bearing supports, and sealing means on both shafts between the bearing supports and the chamber, said sealing means comprising spaced seals separated by an opening into which liquid or lubricant, as the case may be, may leak upon the partial failure of either of the seals.

12. In a pump for handling fluids, a casing provided with a fluid chamber, a rotary pump in the chamber comprising a rotatable cylinder, a rotor mounted in the cylinder in eccentric tangential relation and having an axially extending trunnion shaft, means for introducing fluid into the cylinder and subsequently discharging it including a passage in the shaft, means for rotating the cylinder and rotor to produce a pump action therebetween, a conduit chamber associated with the shaft, a bearing support for the shaft between the fluid chamber and the conduit chamber, means for introducing a lubricant into the bearing support, sealing means located between the bearing support and each of said chambers, said sealing means each comprising spaced seals separated by an opening into which fluid or lubricant, as the case may be, may leak in the event of partial failure of either of the seals.

13. In a rotary pump, a rotary pumping couple including a cylinder wall and end walls together forming an outer wall of a pumping chamber, a rotor therewithin in tangential relation to the cylinder wall to form the inner wall of the pumping chamber, a vane dividing the chamber except when adjacent the point of tangency, inlet and outlet ports communicating with the chamber on opposite sides of the vane and one of the

ports extending through the outer wall of the pumping chamber, and a housing around the pumping couple communicating with the last-named port, and means relatively stationary with respect to the pumping couple and having a surface which engages the surface of said outer wall and closes said one port when the vane is approximately at the position of tangency to prevent reverse flow of fluid through said one port.

14. In a rotary pump, a pumping couple including a cylinder wall and a piston eccentrically disposed in tangential relation to the cylinder wall, end walls associated with the cylinder and the piston to form a pumping chamber, a vane dividing the pumping chamber except when ad-

5 jacent the point of tangency, and means for rotating at least one of the members of the pumping couple to cause a relative rotation between the vane and the point of tangency, inlet and outlet ports communicating with the two parts of the pumping chamber, the inlet port extending through a rotating surface of the pumping couple, and a stationary valve member positioned to engage the surface and close said inlet port when the vane is adjacent the point of tangency to prevent reverse flow of the pumped fluid through said inlet port, while leaving the inlet port open during a major portion of the revolution of the rotary member.
